UNITED STATES PATENT OFFICE.

FRANK W. ADSIT, OF MINNEAPOLIS, MINNESOTA.

TELEPHONE LOCKOUT SYSTEM.

1,217,081.

Specification of Letters Patent. Patented Feb. 20, 1917.

Application filed May 17, 1915. Serial No. 28,632.

To all whom it may concern:

Be it known that I, FRANK W. ADSIT, a citizen of the United States, residing at Minneapolis, in the county of Hennepin and 5 State of Minnesota, have invented certain new and useful Improvements in Telephone Lockout Systems, of which the following is a specification.

My invention relates to means for preventing parties on a telephone party line from listening in on the line when it is in use by another subscriber, and refers more particularly to that class of telephone lines known as common battery or central energy 15 lines.

The drawing, which forms a part of this specification, discloses a pair of line wires A adapted to be connected to any type of common-battery exchange.

20 At stations 1, 2 and 3, the ordinary common-battery telephone set such as 4, 4', 4'', is connected by wires 5, 5', 5'' to one side of the line A, and the other side of the telephones are connected to the lock-out attachments 6, 6', 6'' by wires 7, 7', 7'', respectively. The other side of the line A is brought into the lock-out attachments by wires 8, 8', 8'' and 9, 9', 9''.

When the subscriber at station 2 removes 30 his receiver from the hook, current is fed out onto the line A through any suitable means at the exchange, and passing through the winding 10', wire 11', contact 12', wire 8', completes the circuit and serves to signal 35 the central operator a connection is wanted.

It will be noted that the armature 13' will be attracted by the coil 14', thus opening the contact 15', which is of the type ordinarily called a follow contact and does not 40 break until the contact 16' has been made.

The opening of the contact 15' renders stations 3 and 3' inoperative, as it has opened one side of the line leading to these two stations.

45 The current flowing on the line A through the set 4' at station 2 also flows through the winding 20 at station 1, contact 15, and out to the line again on wire 8, thus operating the armature 23 by its attraction to the core 24, in this manner rendering the telephone 4 at station 1 inoperative through the opening of the contact 12.

50 The operation of each attachment is identical. The control of the telephones between a particular station and the exchange 55 is maintained by the operation of the right-

hand coil, as disclosed in the drawing, in each instrument so controlled, and this control over the right-hand coils in the instruments toward the station is due to the current flowing through these coils and the telephone set at the station initiating the call, the current at this station flowing through the left-hand coil, as disclosed in the drawing.

60 The control of stations farther from the exchange than the one initiating the call is directly accomplished by the contact which is broken when the left-hand coil at the station initiating the call is operated.

65 The windings 10, 10', 10'' are preferably of a high resistance and a correspondingly high number of turns to render the coils operative on systems using a high-resistance line relay, and the windings 17, 17', 17'' are 70 of low ohmic resistance, but have sufficient ampere turns to maintain the contacts 16, 16', 16'' after the coils 14, 14', 14'' have been operated.

75 The windings 17, 17', 17'', being of low ohmic resistance, afford a sufficient current supply for battery feed, and the non-inductive windings 18, 18', 18'' are utilized to allow the voice currents to pass through the attachment more readily than would the inductive windings 17, 17', 17''.

80 It will be noted that only three attachments are necessary for the operation of a line equipped with four telephones, and two attachments will be sufficient to take care of 85 a three-party line, and, similarly, one attachment would take care of a two-party line.

85 In case of a reverting call, where station 3 was calling station 2 on the same line, 90 for example, the central operator would be signaled in the usual manner, but would inform the subscriber the call was on his own line and ask him to hang his receiver on the hook while the party wanted was being 95 rung.

100 If the party called responds while the bell is still being rung, and the party calling also takes his receiver from the hook while the ringing current is on the line, 105 neither party's set will be operative until the operator removes the ringing current by the usual manner of throwing her ringing key, as the ordinary practice is to have the line dead or free from battery current when 110 the ringing current is on. When the battery current is restored to the line through

the restoring of the ringing key to its normal position, the current at station 2 will flow through both coils, hence both armatures 13' and 23' will be actuated, and the 5 party at station 2 will be in on the line. The party at station 3 will be connected to the line with the party at station 2 in a similar manner, while parties beyond station 3 will be cut off through the opening of 10 contact 15'' and parties between station 2 and the exchange will be cut off by the operation of the right-hand coil at each station, as shown in the drawing.

While I have described and illustrated my 15 invention with one particular arrangement of parts and circuit, I do not wish to be understood as limiting myself to this particular arrangement, as it is evident the same result may be accomplished by a number 20 of different arrangements within the scope of my invention as set forth in the following claims.

I claim:

1. In a telephone lock-out system, the 25 combination of a pair of line wires adapted

to be connected to a common-battery exchange, two subscribers' stations associated with said pair of line wires, means associated with one of said stations to disconnect the other of said stations when the first of 35 said stations is being used, and a second means associated with said means to render it inoperative when said stations are both actuated with no battery on said pair of line wires.

2. In a telephone lock-out system, the combination of a line circuit adapted to be connected with a common-battery exchange, two subscribers' stations connected with said line circuit, a lock-out mechanism connected with said line circuit and said stations and adapted to disconnect either of said stations when the other station is actuated, and means in said lock-out mechanism adapted to connect both of said stations to said line circuit when battery is applied to said line circuit after both of said stations have been actuated.

FRANK W. ADSIT.
